UNITED STATES PATENT OFFICE.

SARAH A. ULMER, OF PORTLAND, MAINE.

EGG-BEATER.

SPECIFICATION forming part of Letters Patent No. 224,117, dated February 3, 1880.

Application filed April 11, 1878.

To all whom it may concern:

Be it known that I, SARAH A. ULMER, of Portland, in the county of Cumberland and State of Maine, have invented certain new and useful Improvements in Egg-Beaters; and I do hereby declare that the following is a full, clear, and exact description of the invention, that will enable others skilled in the art to which it appertains to make and use the same, reference being had to the accompanying drawings, forming a part of this specification, in which—

Figure 1 is a perspective view, part of the casing being broken away to show the paddle. Fig. 2 is a detail, showing the latch. Fig. 3 is a detail, showing the shaft; and Fig. 4 is also a detail, showing another method of attaching the paddle to the shaft.

The object of my invention is the improvement of egg-beaters.

The egg-beaters hitherto in use are objectionable on account of the time required in using them and the imperfect character of the result obtained. It is the result of my observation that eggs are most thoroughly and quickly beaten by subjecting them to the blows, in rapid succession, of smooth-surfaced wires, and that anything of a sharp cutting nature destroys the fiber of the egg, which should be preserved. This principle is embodied in my device, which may be described as follows:

a represents the casing or vessel in which the eggs are placed. Preferably the bottom should be circular in form, as shown in Fig. 1. *b* is the cover, which is provided with air-holes *c c*. Within this casing or vessel is placed the paddle, which consists of the shaft *d*, with its arms *e* and the wires *l*.

In the drawings the arms are four in number, and are fixed to the shaft at right angles with it and with each other. A larger number of arms may be used, provided the number be not so large as to bring them too near together. The wires *l l* have their ends inserted into the arms, as shown in Fig. 1, and may be varied in number, the proportionate distance between the wires being substantially as shown in Fig. 1.

The shaft *d* may be made solid except at one end, which has a square opening to receive the pinion-shaft *f*, the inner part of which, *j*, is

also made square. The solid end of the shaft should be journaled in the side of the casing in such manner that there be no opening from the interior to the exterior. The pinion-shaft passes through the opposite end of the casing, and any of the common devices may be used to render the opening close enough around the shaft to prevent leakage. This shaft *f* is kept in position by means of the ring *t* on the shaft and the latch and catch *g* and *n*. (See Figs. 1 and 2.)

The pinion *h* meshes into the larger cog-wheel *s*, to which power is applied.

In Fig. 4 another method of connecting the paddle with its shaft is shown. *r* is a continuous shaft, square at either end, just within the bearings. The arms are fixed to the circular metal piece *y*, having at the center a square opening for the insertion of the shaft, which is kept in position by the latch in the same manner as the pinion-shaft *f*.

The operation of the egg-beater is obvious. The paddle is removed for the purpose of cleaning by lifting the latch *g* and withdrawing the shaft, to which the pinion is attached, from the casing.

I do not claim such a device as shown in Letters Patent No. 117,982, granted to Daniel B. Clayton, August 21, 1871, wherein the beating is effected by a thin flat beater entering the substance to be beaten edgewise; nor that shown in Letters Patent No. 151,784, granted to J. F. Landis, June 9, 1874, wherein the beaters are attached to the shaft at right angles thereto.

What I claim as my invention, and desire to secure by Letters Patent of the United States, is—

In an egg-beater, the combination of a casing with a horizontal shaft, *d*, therein, carrying arms *e e*, supporting between them a series of horizontal wires, the various parts forming the beating-surface being of round or curved cross-section, substantially as and for the purposes set forth.

In testimony that I claim the foregoing I have hereunto set my hand this 8th day of April, 1878.

SARAH A. ULMER.
